COMBUSTION TURBINE

Oles B. Jacobs, Chicago, Ill.

Application November 11, 1935, Serial No. 49,134

6 Claims. (Cl. 60—42)

This invention is a rotary combustion turbine for the purpose of providing power to vehicles, pulleys and power take-offs of all kinds.

An important object of my invention is the provision of an internal combustion engine capable of extreme light weight construction with high power development per pound of weight.

A further object of my invention is the provision of a combustion turbine without piston or valve construction as commonly found in the conventional type internal combustion engine.

A further object of my invention is the provision of a combustion turbine using a volatile gas as a starting and heating medium and the further coincident use of self-generated steam or water vapor as a medium of propulsion and power generation.

A further object of my invention is the provision of a distinctly simplified form of combustion turbine construction.

A still further object of my invention is the provision of a low cost combustion turbine where the economy is due to the elimination of many parts commonly used in the art.

A still further object of my invention is the provision of a combustion turbine having an extremely low cost of operation by reason of the use of low grade fuels and water vapor as sources of power.

A further object of my invention is the provision of a combustion turbine capable of both extremely low and extremely high speeds.

A further object of my invention is the provision of an engine which will make the use of a conventional gearshift, other than reverse, unnecessary when used on passenger vehicles such as automobiles, boats and the like.

Other and still further objects of my invention will be apparent from the disclosures in the specifications and accompanying drawings.

The invention in preferred form is illustrated on the drawings and hereinafter more fully described.

On the drawings
45 Figure 1 is a front sectional view of the internal combustion engine taken approximately on the line 1—1 of Figure 2 showing details of its internal construction.

Figure 2 is a side sectional view of the internal combustion engine taken approximately on the line 2—2 of Figure 1 showing internal construction of the rotor.

Figure 3 is a frontal detail drawing of the rotor, showing several sections thereof removed

to indicate both external and internal construction of said rotor.

Figure 4 is a side view of rotor showing in detail the curvature of the surface ribbing and cut away in section to show side detail of internal valve and water discharge outlets.

Figure 5 is a drawing illustrating the directionally opposed ribbing of the casing and rotor.

Figure 6 is a cross sectional view of the rotary compressor taken on the line 6—6 of Figure 1 showing the water jacketing, valve and eccentric detail.

Figure 7 is a front elevational view of the eccentric and compressor valves, without the compressor casing, broken to show the vane valves on the rotary eccentric and the delivery channels in the eccentric of said compressor.

Figure 8 is a cross sectional view taken on the line 8—8 of Figure 1, illustrating the annular groove and holes which carry gasoline vapor into the rotor.

Figure 9 is an enlarged sectional view taken on the approximate line 9—9 of Figure 1, illustrating the water passages which carry water from the water jacket into the rotor.

Figure 10 is a side elevational view of the starting wheel and the cam and pin which fits into a selected hole in said starting wheel or gear and positions the rotor for draining fluid from the same.

As shown on the drawings

Reference numeral 11 designates a geared starting wheel rigidly fastened or keyed to the axle 17 of the engine. If desired a projecting bolt forming a handle or the like 12a may be attached to this gear to operate the same as a crank in starting the engine. Reference numeral 12 designates the driving gear of a starter which operatively engages the starting wheel 11 of the engine.

Reference numerals 13 and 14 illustrate a pin and cam construction which may be bolted to the carburetor intake pipe or other supporting means. In extended position the pin 13 engages a slot in the starting gear 11 holding the gear and attached shaft and rotor in a fixed position to facilitate ready draining of fluid from the rotor as hereinafter more fully described. In retracted position the pin 13 is fixedly held from contact with said gear 12.

This engine makes use of a conventional type carburetor (not shown) attached to a fuel tank (not shown) which allows a mixture of gas and air to be sucked into the engine through the intake pipe 15.

55

This intake pipe 15 is rigidly attached to the casing 16 which at this point encloses the axle 17, allowing the gas mixture to pass through the annular groove 18 and through the holes 19, thence into the feed line 21 which is hollowed in the central drive shaft 17, thence to the fuel compressor described hereinafter. On either side of said annular groove 18 are packing rings 20 to prevent leakage around the sides of shaft 17 and to insure the passage of the gas mixture into the feed line 21, and thence into the compressor.

The compressor as illustrated consists of a cylindrical eccentric 22 fixedly mounted on drive shaft 17 as shown in Figures 1, 6 and 7. Within said eccentric are ball valves 22a and 22b, valve 22a connecting with feed line 21 through duct 21a and being so seated that the said duct may be closed, such closure preventing any back pressure 20 of gas toward the carburetor. Valve 22a is completely closed at all times from the compression side of said chamber by a splined slide 23 which covers said valve and fuel duct 21b and permits access of fuel to fuel duct 21b and duct 21c through the center of eccentric 22, through portion 24 of drive shaft 17, and said duct 21c is open at all times to the intake side of said compressor as eccentric 22 revolves with the axle 17.

Ball valve 22b is open at all times to the compression side of said compressor, connecting therewith by means of fuel duct 21d with fuel line 21e in the interior of drive shaft 17, whence it is conducted into firing chamber as described hereinafter.

Machined on the outer surface of eccentric 22 and extending from the ports of intake valve 22a and exhaust valve 22b in the direction of the rotation of said eccentric, are annular grooves, the numeral 22c referring to the groove on the intake side and 22d referring to that on the exhaust side. As shown in Figure 7, these grooves rotate immediately under vane valve ports 21b and 21c respectively, each groove being approximately one sixth the circumference of said eccentric.

As shown in Figures 1 and 6, reference numeral 25 illustrates the cylindrical casing of the compressor, said casing being mounted so that all sides of the same are substantially equidistant from the center line of drive shaft 17. Movable 50 mounted on the eccentric 22 by means of splined circular rings 26 are reciprocating valves 27 carrying vanes 27a mounted in movable blade or vane guides 28. The inner edges of said circular rings 26 are splined inwardly, as illustrated in Figure 7, 55 contacting the oppositely cut away outer edges of said reciprocating valves 27, allowing reciprocal motion of the valves and defining their movement relative to eccentric 22. Behind the vane guides 28 are spaces 28a which permit reciprocal motion of vanes 27a. This space 28a is jacketed from the water ports in casing 25 which otherwise surrounds all sides of said compressor casing.

Bored through rotary valves 27 through the semi-cylindrical portions thereof, both in front of and behind vanes 27a and at positions in registry with the eccentric grooves 22c and 22d, and their corresponding valves, are a plurality of vane valve ports 21b and 21c, referring respectively to intake and exhaust portions of said vane valves.

Packing rings 20a are placed at both ends of said compressor to prevent passage of gas mixture from the compressor around the outside of shaft 17 and to insure passage of gas mixture through proper channels.

Enclosed in fuel duct 21e is a ball valve 29 so seated that vaporized fuel can pass into the firing apertures 30 through fuel duct 21f in the rotor, but preventing back pressure into the compressor when the mixture is exploded. In passing to the 5 firing apertures the vaporized fuel passes through holes 19 into fuel duct 21 thence into duct 21a past ball valve 22a through ducts 21b and 21c through ports 21b to an intake side of said compressor. As eccentric 22 rotates forcing valves 27 10 into close proximity to the inner wall of the compressor casing the gas is compressed and is forced through ports 21c past ball valve 22b into duct 21d thence into duct 21e, past ball valve 29 and is discharged through ducts 21f into the firing apertures 30.

The firing apertures 30 are placed in positions on opposite sides of the rotor near the center of the rotor 31. The sides of these apertures have an outward slope in the direction of the periphery 20 of the rotor to give the exploded gases the proper initial direction toward the exhaust ports.

Screwed into ports 32a through the rotor casing 33 are conventional spark plugs 32, the functioning of these spark plugs being controlled by a conventional condenser and distributor mechanism, which is not illustrated, but which is geared to said engine in an appropriate position and which is so timed as to intermittently throw a spark to ignite the fuel injected into the apertures 30 as they pass said spark plugs in rotation.

Rotor 31 and rotor casing 33 are in close juxtaposition at all points and each have oppositely defined curved angularly projecting fins or ribbing on their entire exposed surfaces, 31a representing the plurality of projecting fins or ribbing on the rotor and 33a representing that on the casing, so that the expansion of the exploded gases between said opposed fins or ribs will give motion to the rotor.

The numerals 31b and 31c refer to internal and external laterally and perpendicularly extending rotor rims respectively, each of which is mounted on said rotor or may be formed integral with the rotor as shown in Figures 1 and 3 and each being 45 grooved or ribbed on all exposed surfaces, the said grooves or ribs all extending in a direction opposite to the grooving or ribbing on the rotor casing. The exploding gases must pass around the edges of these rims to reach the exhaust ports 50 34 which are enclosed by the exhaust pipe 35. The exhaust pipe 35 entirely surrounds the rotor casing, its size increasing as it approaches the pipe 35a and terminating in said pipe 35a, which directs the exhaust fumes wherever desired.

The rotor 31 is so formed as to have an internal space 36, as shown on the drawings Figs. 1 and 3, into which water may be drawn from the water jacket of the rotor casing in the manner and for the purposes hereinafter more fully set out.

The rotor casing 33 is jacketed, as shown in Figure 1, to allow all necessary circulation of water around the sides of the same. The compressor may also be jacketed, as shown in Fig. 1, if desired. Relatively limited water circulation is 65 to be provided in the casing 33 opposite the water outlet passages 50. The casing 33 must be allowed to become hot enough to convert the water passing from passages or ducts 50 into steam, giving additional explosive and propulsive energy to the 70 rotation of rotor 31.

As shown in Figures 1 and 9, reference numeral 37 indicates a water passageway leading from the jacket in casing 33 to an annular groove 38 in the drive shaft 17, connecting by means 75

of holes 39 with water ducts 37a in the rotor and leading into the central portion thereof. To prevent the flow of water to any spot other than as indicated, packing rings 40 are employed and mounted, as shown in the drawings, on either side of the annular groove 38.

To regulate the flow of water from the jacket into the rotor a manually operated needle valve 41 is employed. This valve is mounted in the rotor casing 33 and so seated that it regulates and controls the flow of water from the rotor water jackets into the internal portion 36 of the rotor 31.

As particularly illustrated in Figs. 1 and 9, the rotor casing 33 in its preferred form is provided with a series of enlarged water chambers 33b arranged in a circle and being in general communication with the other water jacketing of the rotor casing. Free circulation of water between water chambers 33b is provided by the connecting passageways shown on the drawings and indicated by numeral 33c.

Reference numeral 45 indicates the internal rotor water ports which connect with outlet jets 47, communication therebetween being permitted by means of centrifugally operated valves 46, which are adapted to be opened by centrifugal force of the rotor against the action of respective spring 46b, said spring normally closing valves 46 against respective seats 46a.

As indicated in Figure 2, the water ports 45 originate near the internal hub of the rotor and terminate in the valve seats 46a and are closed by respective valves 46, each of which is fastened at one end by bolt 46c and held in a normally closed position by spring 46b, the tension of which is subject to regulation by means of screw 46d.

The reference numeral 50 indicates the water discharge ducts of which there are two to each valve, one on each side thereof, discharging from the outer surface of the inner rotor rim 31b against the opposed fins or ribbing of the rotor casing. Enclosed within these ducts are ball valves 51 which allow outward passage of water vapor but do not allow passage of gases back into the rotor.

Reference figure 52 indicates the hinged rotor drain valve mechanism which is set in an aperture 53 in the outer rim of the rotor 31, said valve being retained in a normally closed position by the spring mechanism 52a behind the retaining screw plug 52b. The numeral 54 is used to illustrate the drain valve, which is normally held in closed position against valve seat 54a by coil spring 54b. Illustrated and indicated by numeral 55 are the screws which hold the outer rotor rim 31c in place.

In Figure 2 a detail of the rotor drain mechanism is shown, 49a being a crank on which is mounted worm gear 49b which is meshed with segmented gear 49c. A finger-like integral projecting arm 49d is formed integral with gear 49c. By turning crank 49a the projecting arm 49d may be moved into or out of contact with rotor drain valve arm 52 when the rotor 31 is in proper position to permit such contact. This position may be determined by positioning bolt 13 into proper groove in starting wheel 11.

The engine as described above may be modified by the inclusion therein, as indicated in Figure 1, of pipes 56 connected with a suitable vaporizing mechanism, for the use of low grade fuels such as fuel or furnace oil or the like. These pipes terminate in outlet jets 56a which

discharge through the side of rotor casing 33 directly opposite firing apertures 30. This construction is, of course, optional it being in no manner necessary to the operation of the engine as otherwise set out, but when thus operated the flow of high grade volatilized fuel may be diminished or entirely shut off and lower grade fuel employed.

To start the engine, the pin 13 is first disengaged from the geared starting wheel 11, needle valve 41 is turned down to prevent water from entering the rotor; crank 49a is then turned so that elements 49c and 49d are withdrawn from contact with rotor drain valve arm 52 and valve 54, which closes under the pressure of spring 52a. The engine may be cranked by a crank 12a on wheel 11, or the engine may be started by means of a mechanical starter through pinion gear 12. The rotation thus given the drive shaft causes the compressor to function, sucking a volatile mixture of aerated gasoline vapor from the carburetor through intake pipe 15, thence through annular groove 18 and holes 19 into the fuel duct 21.

The mixture then passes through fuel duct 21a past ball valve 22a through ducts 21b and 21c into an intake section of the compressor. As eccentric 22 rotates with the axle 17, the rotary valves, which are retained in position at either end by splined rings 26 and are guided in their reciprocal motion by the vanes 27a sliding in vane guides 28, are forced into close contact with the compressor casing 25. This action reduces the space between said valves and surrounding casing and causes the sides of the same positioned on the eccentric to assume a relatively spaced position. The gas thus compressed, having no other available outlet is forced through ports 21c past ball valve 22b into fuel duct 21d, thence through duct 21e past ball valve 29, thence through fuel ducts 21f in the rotor to the firing apertures 30.

As one section of the rotor is compressing gas and discharging it as indicated above, other sections are drawing the gas mixture from the opposite side of the eccentric through fuel duct 21c, the valves 27 being pulled by splined circular rings 26, from close contact with compressor casing 25. As this occurs the circular portions of the valves 27 are relatively close together, the vanes 27a being inwardly extended almost their full length. Further rotation of the eccentric causes a reversal of this position of the valves, causing compression in that section in nearest contact with eccentric 22 and corresponding intake action on the valves formerly on compression.

As the gas mixture reaches the firing aperture 30 the spark emitted by the spark plugs causes the mixture to ignite. The exploded mixture having no other outlet is forced between the oppositely grooved sides, 31a and 33a, of the rotor 31 and the rotor casing 33 around the inner rotor rim 31b and the outer rotor rim 31c, travelling in all a distance of several times the radius of the rotor, before reaching exhaust ports 34 at the periphery of rotor casing 33.

As the rotor gains speed under force of the internal gas explosions the water valve 41 is opened allowing water to flow through duct 37 to annular groove 38, through holes 39, thence through duct 31a and into the space 36 in the rotor.

When section 36 is filled with water the water covers water port 45 and centrifugal force causes

it to reach water valve 46. Under the combined pressure of heated expanded water and centrifugal force, this valve opens allowing water to pass through the same into ducts 47 thence into passages 50 past ball valves 51 where the water is discharged from the outer periphery of the inner rotor rim 31b.

As the discharged water and water vapor are thrown into contact with the heated rotor casing 10 (which at this point is not water jacketed for the express purpose of providing a heated surface) numerous further explosions caused by the mixture of gas and water vapor take place between the opposed grooved surfaces of the lateral rotor rims and the surrounding casing imparting additional propulsive force to the rotor as the gases move outwardly seeking the exhaust ports 34.

The speed of the engine may be controlled by 20 regulating the intake of fuel through the conventional carburetor and auxiliary fuel feed ducts 56 in manner well known in the art of vaporizing fuel for use in engines and by regulating the water flow into the rotor by means of valve 41, or 25 both.

Although the rotary compressor is described at some length and it is believed that a rotary compressor would be most satisfactory in use with this engine, it is obvious that any means of 30 feeding a compressed intermittent flow of volatile fuel into the firing apertures would function.

Shaft bearings 43 and 44 support the drive shaft 17 and aid in reducing friction, but I may employ such additional bearing surfaces and lubrication means as shall be most successful in 35 promoting the efficient operation and main processes of this internal combustion engine.

While I have described and illustrated my engine in considerable detail, I do not wish to be limited to the exact construction disclosed herein other than is necessitated by the scope of the appended claims.

Having thus described my invention, I claim:

1. In a combustion turbine, a fixed water jacketed casing, a plurality of radially extending ribs projecting from the inner surfaces of said casing, a hollow rotatable shaft extending through said casing, an externally angularly ribbed hollow rotor mounted on said shaft, said rotor having a plurality of apertures near the axis thereof, means for introducing water from said water jacketed casing into said hollow rotor through said hollow shaft, a plurality of outlet ports in said rotor, adapted to be opened by centrifugal force generated by rotation of said rotor permitting emission of water from within said rotor into said casing, said casing being adapted to vaporize said water by explosion generated heat, and means for introducing and exploding a volatile fuel in said apertures in said rotor to generate heat and cause rotation of said rotor, the steam generated by the water ejected from said outlet ports in said rotor imparting additional rotative force to said rotor.

2. In a combustion turbine, a housing, radially extending protruding fins formed integral therewith on the inner surfaces of said housing; an axle mounted therein and passing therethrough; 70 a hollow rotor having a plurality of angularly formed apertures formed therein and extending therethrough mounted on said axle; radially extending protruding fins formed integral with said rotor angularly mounted opposite to the fins on the rotor casing; means for introducing water

into the hollow interior sections of said rotor and a plurality of centrifugally operated valves adapted to allow the emission of water from said rotor against the inner surface of said housing thereby generating steam and water vapor; means to introduce a volatile fuel into said casing and explode the same within said rotor apertures and means extending through said casing and discharging opposite the apertures in said rotor adapted to introduce a secondary supply of fuel into said rotor apertures and means to explode the same, thereby imparting motion to said rotor.

3. In a combustion turbine an enclosed housing, a centrally bored axle mounted therein and extending therethrough, a rotor having a plurality of apertures near the axis thereof mounted on said axle, said rotor having a plurality of substantially parallel curved radially extending ribs formed integral therewith, said ribs forming angular grooves opening opposite to the direction of rotation, said rotor having a hollow interior chamber, said axle and said rotor having communicating passageways therein permitting inlet of water into the interior chamber of said rotor, a plurality of valve controlled outlet ports on the periphery of said rotor, means connected to said valves and responsive upon rotation of said rotor to open and cause emission of water from within said rotor into said housing, the heat of said housing causing vaporization and expansion of said emitted water thereby imparting additional rotative force to said rotor; a plurality of substantially parallel radially extending ribs formed integrally with the interior of said housing and radially projecting therein in a direction opposite to the ribs on said rotor but in planes substantially parallel thereto, means for introducing a volatile fuel into said housing and apertures in said rotor, and means for intermittently igniting said fuel, the explosion thus produced in conjunction with said emitted water vapor imparting movement to said rotor.

4. In a combustion turbine the combination of a source of vaporized fuel, a housing, an axle rotatably mounted in said housing, a compressor adapted to compress a volatile fuel said axle having a connecting passageway formed therein at one side thereof adapted to connect said source of vaporized fuel with said compressor adapted to intermittently compress the same, a further passageway in said axle connecting said compressor to a plurality of apertures in a rotor mounted on said axle and rotatable therewith, a rotor having a plurality of angularly formed apertures formed therein adapted to receive the compressed vaporized fuel from said connecting passageway in said axle and a hollowed out internal portion adapted to contain and discharge water, said rotor having a plurality of angularly projecting ribs formed and extending radially thereon, a water-jacketed casing surrounding said rotor, having a plurality of angularly projecting ribs formed and extending radially thereon in planes opposite to the ribs on said rotor, a connecting passageway between the water jacket on said rotor to the axle thereof, a passageway in the axle of said rotor adapted to carry water from the passageway in said jacket, communicating passageways in said rotor connecting to the hollowed out internal portion thereof, adapted to pass water into said rotor, a plurality of centrifugally operated valves in said rotor adapted to pass water from said rotor into said casing, means to explode a volatile gas in the

5 apertures in said rotor, imparting movement to said rotor and generating heat in said casing, the explosion generated heat turning the water passed from said rotor into steam and explosive gas imparting additional rotative movement to said rotor.

5. In a combustion turbine the combination of a source of vaporized fuel, a casing forming a housing an axle rotatably mounted in said housing, said axle having a connecting passageway formed therein at one side thereof adapted to connect said source of vaporized fuel with a compressor, a compressor adapted to intermittently compress vaporized fuel, a further passageway in 10 said axle connecting said compressor to a plurality of apertures in a rotor mounted on said axle and rotatable therewith, a rotor having a plurality of angularly formed apertures formed therein adapted to receive the compressed vaporized fuel 15 from said connecting passageway in said axle, and an annular rim on the periphery thereof, said rotor and rim having a hollowed out internal portion adapted to contain and discharge water, said rotor having a plurality of angularly projecting ribs formed and extending radially thereon, a water-jacketed casing surrounding said rotor, having a plurality of angularly projecting ribs formed and extending radially thereon in planes opposite to the ribs on said rotor, a connecting passageway between the water jacket on said rotor, a manually operable valve in said passageway adapted to control the flow of water therethrough, a passageway in the axle of said rotor adapted to carry water, communicating 20 passageways in said rotor connecting to the hollowed out internal portion thereof adapted to pass water into said rotor, a plurality of centrifugally operated water valves in said rotor 25

adapted to pass water from said rotor into said casing, means to explode a volatile gas in the apertures in said rotor, imparting movement to said rotor and generating heat in said casing, the explosion generated heat turning the water passed from said rotor into steam and explosive gas imparting additional rotative movement to said rotor. 5

6. In a device of the described class, the combination of a compressor adapted to compress an explosive gas, connecting passageways between said compressor and a rotor in a casing enclosing said rotor, a hollow rotor having a plurality of apertures near the hub thereof into which the explosive gas compressed by said compressor may be emitted through said connecting passageways, means to explode said explosive gas in said rotor apertures, a plurality of arcuately disposed ribs on said rotor formed and extending from the axis thereof angularly opposite to the direction of rotation of said rotor, a casing enclosing said rotor, a plurality of arcuately disposed and arcuately extending ribs on the inner surfaces of said casing, curved in the direction of rotation of said enclosed rotor, connecting passageways between a 10 source of water and the internal hollow portion of said rotor, a plurality of centrifugally operable valves near the periphery of said rotor adapted to permit water and water vapor to pass from said rotor against the inner walls of said rotor casing, the explosive gases exploded in said rotor apertures imparting initial rotation to said rotor and generating heat and causing the water expelled from said hollow rotor to be converted into steam within said rotor casing imparting additional propulsive force to said rotor. 15 20 25 30 35

OLES B. JACOBS.
